UNITED STATES PATENT OFFICE.

AUGUSTUS F. NAGLE, OF CHICAGO, ILLINOIS.

SAFETY-GAGE.

SPECIFICATION forming part of Letters Patent No. 398,069, dated February 19, 1889.

Application filed October 20, 1888. Serial No. 288,703. (No model.)

To all whom it may concern:

Be it known that I, AUGUSTUS F. NAGLE, of Chicago, Illinois, have invented certain new and useful Improvements in Safety-Gages, of which the following is a specification.

The main object of my invention is to provide an electric safety-gage apparatus which shall be complete in itself and ready for use by simply connecting it with the steam-boiler, or other device to which it is to be applied.

Another object is to provide an electric contact in which the contact-points are brought together by an appreciable force as distinguished from those in which the contact is made by a needle moving over a dial in which the force is necessarily very light.

Other objects will be apparent from the structure of the apparatus and the subjoined description.

20 In the accompanying drawings I have represented a safety-gage containing my invention and set to operate at the upper limit of pressure.

In the drawings, Figure 1 is a perspective view of the complete apparatus, with the door of the battery-box removed to show the battery within. Fig. 2 is a sectional elevation showing the pressure-chamber, diaphragm, spring, and contiguous parts.

30 In the figures, 1 is a box, stand, or bracket. 2 is the battery contained therein.

3 is an electric bell.

4 is the part of the box in which the bell-magnet is contained.

35 5 is a pressure-chamber attached to the bracket.

6 is a pipe through which communication is established between the steam-boiler or other device and the pressure-chamber.

40 7 is a flexible diaphragm in the upper part of the chamber.

8 is a post in the chamber to support the diaphragm against the pressure of the spring above it.

45 9 is a plunger attached to the diaphragm.

10 is a spring bearing down upon the plunger and contained in the tube 11.

12 is a screw-cap, against which the upper end of the spring bears. By screwing the cap 50 down or up the tension of the spring may be increased or diminished.

13 is an arm connected to plunger 9, so as

to move with it, and 14 is a contact-point on the arm.

15 is a contact-spring, against which point 55 14 is brought by the upward movement of plunger 9.

16 and 17 are connecting-wires.

18 is an index on tube 11 to show the tension of the spring. 60

The lower edge of cap 12 may be also graduated, so as to show the fractional parts of the divisions on scale 18.

19 is an ordinary steam-gage, which may be applied to my apparatus for convenience, but 65 is not necessary to it, and as it forms no part of my invention I will not further describe it.

In operation, spring 10 having been adjusted to the required tension by the screw-cap, the steam or other fluid under pressure 70 enters chamber 5 through the pipe 6 and acts upon the under side of the diaphragm. When its pressure rises to the safety limit at which the spring is set, and which is indicated by the index at 18, the diaphragm and plunger 75 9 will be forced upward against the pressure of the spring and point 14 will be brought in contact with spring 15, thus closing the electric circuit, and the bell 3 will ring and call the attention of the attendant. The contact-points being brought together by the direct pressure of the fluid on the diaphragm will not derange the apparatus, as would be the case if the contact were made through intermediate levers, hands, or needles, in which case the 80 85 indications of the pressure would become unreliable and unsafe in their readings.

It is obvious that many structural variations and modifications may be made in this apparatus to suit the varying requirements in 90 practice and still retain all of the advantages of the apparatus—such as having a device which is complete in its requiring only a single connection to put it in use, and such as having an appreciable force to bring the 95 contacts together and close the circuit—and the other advantages of my invention; but such modifications and variations, where made by the mechanic from his knowledge and skill, would not be a departure from the spirit 100 of my invention.

What I claim is—

1. In an electrical pressure-indicator, the combination, with the chamber 5 and the con-

tact-arm 15, of the shell 11, the movable plug 9, provided with a contact-point, 14, a spring, 10, bearing upon the plug, a diaphragm, 7, mounted in the chamber 5 and adapted to 5 actuate the plug, which is independent of the diaphragm, a pipe, 6, adapted to convey fluid to the chamber beneath the diaphragm, and electric connections, all arranged for operation substantially as shown.

10 2. In an electrical pressure-indicator, the combination, with the chamber 5 and the contact-arm 15, of the shell 11, provided with a spring, 10, a diaphragm, 7, mounted in the chamber 5, a plug, 9, provided with a contact-point, 14, and resting upon the diaphragm, a stem, 8, adapted to support the diaphragm, and electrical connections.

15 3. In an electrical pressure-indicator, the combination, with the hollow shell 11 and the

chamber 5 and diaphragm 7, of the movable 20 plug 9, resting upon the latter and adapted to complete the circuit, a spring, 10, inserted into the shell and resting upon the plug to act in opposition to the pressure of the fluid, and an adjustable cap, 12, upon the end of 25 the shell adapted to vary the tension of the spring.

4. The combination, with the chamber 5, provided with a diaphragm, 7, and a plug, 9, of the shell 11, provided with a spring, 10, and 30 with a scale, 18, and a graduated adjustable cap, 12, secured to the shell 11 and adapted to vary the tension of the spring.

AUGUSTUS F. NAGLE.
